(57) **CLAIM**

I claim the ornamental design for a pocket adornment, as shown and described.

DESCRIPTION

FIG. 1 is a front elevational view of a pocket adornment showing my new design, where the broken lines showing portions of a person and clothing are included for illustrating environmental structure and form no part of the claimed design.

FIG. 2 is a perspective view of the invention;

FIG. 3 is a rear elevational view of the invention;

FIG. 4 is a front elevational view of the invention;

FIG. 5 is a left-side elevational view of the invention, the right-side elevational view being a mirror image thereof;

FIG. 6 is a top plan view of the invention; and,

FIG. 7 is a bottom plan view of the invention.
